(57) **CLAIM**

The ornamental design for an overcap for injector, as shown and described.

DESCRIPTION

FIG. 1 is a perspective view of an overcap for injector showing the design.

FIG. 2 is an end view of the design of FIG. 1, showing the top end visible in FIG. 1.

FIG. 3 is a side elevation view showing the design of FIG. 1; and,

FIG. 4 is a side elevation view in a direction rotated 90 degrees from the view of FIG. 3 showing the design of FIG. 1.

Nature and intended use of the article in which the design is embodied: A protective overcap for an injector for administering an injection into a human or animal subject; the overcap is removed prior to administration of the injection.

UNITED STATES PATENT AND TRADEMARK OFFICE
CERTIFICATE OF CORRECTION

PATENT NO. : Des. 613,400 S
APPLICATION NO. : 29/348228
DATED : April 6, 2010
INVENTOR(S) : Marc W. Hunter et al.

Page 1 of 1

It is certified that error appears in the above-identified patent and that said Letters Patent is hereby corrected as shown below:

Column 1, Title Page

Item 75, Line 1, "Mark W. Hunter" should read -- Marc W. Hunter, --.

Column 2, Title Page

Item 57, Line 1, "injector," should read -- injector --.

In Description, Line 5-6, "FIG.1; and," should read -- FIG. 1. --.

Signed and Sealed this

Twenty-fourth Day of August, 2010

David J. Kappos
Director of the United States Patent and Trademark Office
